UNITED STATES PATENT OFFICE.

NEWELL P. COWELL, RENSSELAER A. COWELL, AND JOHN F. HERRICK, OF CLEVELAND, OHIO.

CAR-COUPLING.

SPECIFICATION forming part of Letters Patent No. 319,883, dated June 9, 1885.

Application filed March 14, 1885. (No model.)

To all whom it may concern:

Be it known that we, NEWELL P. COWELL, RENSSELAER A. COWELL, and JOHN F. HERRICK, all of Cleveland, in the county of Cuyahoga and State of Ohio, have invented certain new and useful Improvements in Car-Couplings; and we do hereby declare the following to be a full, clear, and exact description of the invention, such as will enable others skilled in the art to which it pertains to make and use the same.

Our invention relates to improvements in car-couplings, and especially to the class of hook-couplers with pivoted draw-bar heads, the object being to provide the head with a pocket and pin for receiving and securing the ordinary link; and a broad flat surface for a buffer, and means for securing the head in a position that presents the buffer and pocket fairly to the opposing coupler—that is, with the buffer approximately at right angles to the line of the draw-bar—by means of which, with the head secured in such position, the device acts substantially as an ordinary link car-coupler. A further object is to provide a sliding bar operating in an inclined chamber in the pivoted head, and so arranged that when the coupling-pin is elevated the bar will slide by gravity toward and under the point of the coupling-pin and hold the latter elevated, and the bar will be forced back by the link when the latter enters the link-pocket, and thereby release the coupling-pin, that will then descend by gravity and couple the link.

With these objects in view our invention consists in certain features of construction and in combination of parts hereinafter described, and pointed out in the claims.

This invention is designed as an improvement on a device for which Letters Patent of the United States, No. 278,403, dated May 29, 1883, were granted to Newell P. Cowell.

In the accompanying drawings, Figures 1 and 2 are plan views in section of our improved coupler, the former showing the head in position for a link-coupler, and the latter showing the head in position for a hook-coupler. Fig. 3 is a view in perspective of the pivoted head, showing the link-pin elevated and the sliding bar engaging the link-pin. Fig. 4 is a view in perspective of the forward portion

of the draw-bar. Fig. 5 is a view in perspective of the pivoted head detached from the draw-bar. Fig. 6 is a view in perspective of the key C detached from the draw-bar. Fig. 55 7 is a view in perspective of the sliding bar in position engaging the link-pin.

A represents the draw-bar, B the head, and C the key that locks the head in its closed position. The front end of the draw-bar is 60 provided with jaws a, that embrace a portion of the head and fit into the depressions thereof, b, and the draw-bar and head are secured together by the pivotal pin D. At the rear portion of the jaws is the recess A' in which 65 the key C operates. The draw-bar is provided with a ledge, d, and the key with the ledge c', and between these ledges and abutting against each operates the spring G, that holds the key in position in its seat. The key 70 also has a flange, e, that, when the parts are in the position shown in Fig. 2, engages the shoulder b and holds the head from turning or uncoupling. By withdrawing the key, by means of the attached chain, to the position 75 shown in dotted lines in Fig. 2, the flange e is disengaged from the shoulder b', so that the head is free to open or uncouple, and turns out to the position shown in Fig. 1. Meantime the key, if left free, is returned to its 80 former position by the recoil of the spring G. The key has a recess, c', the shoulders at the ends of which, abutting against the pin d', that passes vertically through the draw-bar, limit the end motion of the key, and the said pin en- 85 gaging the back wall of the recess holds the key in place in that direction. When the head B is turned from the position shown in Fig. 1 to that shown in Fig. 2, the key C is snubbed back and automatically locks the head, all of 90 which is fully described in the former patent aforesaid. The head is provided with the recess or pocket F, to receive a link, L, and preferably of such depth that something more than half the length of an ordinary link can enter 95 the pocket, and with vertical openings f for the coupling-pin f', and has a flat surface, f'', around the pocket F, forming a buffer, all of which are similar to the pocket, pin, and buffer on an ordinary draw-head used with links; and 100 when the head is to be used for a link-coupler it is desirable to secure it in the position shown

in Fig. 1, in which position the face of the buffer is approximately at right angles to the line of the draw-bar. To this end the jaws are provided with the vertical holes *i*, that receive 5 the pin *I*, and the head with the vertical groove *K*, that, when the head is in the position shown in Fig. 1, registers with the corresponding part 10 of the holes *i* and fits snugly the pin *I*, so that the head is rigidly held in this position. When 15 the pin *I* is withdrawn, the head is free to operate, as before, as a hook-coupler. The head *B* assumes the position shown in Fig. 1 every time it is drawn out—that is, every time it is 20 opened or uncoupled from another hook—and it requires only the placing in position of the 25 pin *I* to convert the head into substantially an ordinary link-coupler. The pin *I* is secured to the car by a chain, so that it is always at hand when it is desired to use the head for a link-coupler. With the head secured in the 30 position shown in Fig. 1, and by reason of the pocket and link-pin and the flat broad surface around the pocket forming a buffer, and with both the pocket and buffer fairly presented to the opposing coupler, the device is 35 equally convenient, and operates substantially as an ordinary link-coupler.

M is an inclined chamber in the head *B*, and when the head is in the position shown in Fig. 30 this chamber is on an angle of, perhaps, ten or fifteen degrees (more or less) to the axis of the draw-bar, and at about the same angle with a central line of the link-pocket. This chamber extends from the depression *b* on top of 35 the head into the link-pocket, and slopes upward and outward on an angle of, perhaps, forty-five degrees (more or less) from a horizontal line. The outer end of the chamber will be closed by the upper jaw, *a*, when the parts 40 are assembled. In the chamber *M* operates the sliding bar *P*, that has an easy fit in the chamber, the inclination of the latter being such that the bar, when left free, will slide endwise by gravity toward the link-pin. The 45 movement of the bar is limited outwardly by the said jaw and inwardly by the shoulder *p* on the bar, that engages a corresponding shoulder on the lower wall of the chamber, as shown in Fig. 3, or any suitable stop. 50 When the coupling-pin is raised and the link is withdrawn from the link-pocket, the bar will slide forward until the point of the bar extends far enough under the end of the link-pin to hold the latter elevated. (See 55 Fig. 3.) When the link enters the link-pocket, it will engage the end of the bar and move it back into the chamber *M*, thereby releasing the link-pin, which will fall by gravity and secure or couple the link. When the link 60 shall have advanced in the pocket far enough to push back the bar and release the coupling-pin, it will be advanced far enough to receive the coupling-pin, and be secured or coupled thereby. When the coupling-pin is 65 elevated to uncouple the cars, if it is held a moment, until the link is withdrawn, the bar will secure the pin, as aforesaid, so that no

further attention need be given to it, and the next link that enters the link-pocket will be coupled automatically; also, at any time when 70 the link-coupler is not in use the coupling pin may be inserted and left in position for coupling.

It is found in practice that when two opposing hook-couplers with pivoted heads are 75 each in position opened, and are brought together for coupling, if the engaging faces of the heads are smooth sometimes but one of the heads will close, and in such a case the heads would not be securely locked, but would 80 draw apart when any considerable strain was brought to bear upon them. To remedy this difficulty and insure the closing of both heads, we have provided depressions *S* on the engaging edges of the head. Now, when two opposing heads are brought together, if they have 85 a tendency to slip the one upon the other the somewhat abrupt curves at *s* are brought together, and by means of the projecting parts *s* both heads are forced to a position closed 90 before the heads can pass and hook by each other.

What we claim is—

1. In an automatic car-coupler, the combination of a pivoted head provided with an 95 elongated pocket, a broad flat surface forming a buffer around the pocket, and separate and independent devices for locking the pivoted head in its two positions, substantially as set forth.
2. In an automatic hook car-coupler with a pivoted draw-bar head provided with suitable link-coupling mechanism and a movable key for locking the head to form a hook, a pin inserted in the draw-bar, and an engaging 105 groove in the head for locking the head in position to present the link-coupling face toward an opposing draw-head, substantially as set forth.
3. In an automatic hook car-coupler, the 110 combination, with a pivoted head provided with a link-pocket and buffer-face, and separate and independent devices for locking the head in two positions, of a bar operating automatically in a chamber of the head to engage the 115 coupling-pin when the latter is elevated, and so arranged that the link will force back the bar and release the coupling-pin, substantially as set forth.
4. In an automatic hook car-coupler, a depression or projection on that part of the head that is engaged by an opposing head, for mutually closing both heads in coupling, substantially as set forth.

In testimony whereof we sign this specification, in the presence of two witnesses, this 11th day of March, 1885.

NEWELL P. COWELL.
